United States Patent Office

Des. 186,868
Patented Dec. 22, 1959

186,868

CAP

Joseph De Grazia, Washington, D.C., assignor to the United States of America as represented by the Secretary of the Army

Application July 2, 1958, Serial No. 51,637

Term of patent 14 years

(Cl. D3—13)

(Granted under Title 35, U.S. Code (1952), sec. 266)

Figure 1 is a perspective view of a cap embodying my new design;

The invention described herein, if patented, may be manufactured and used by or for the Government for governmental purposes, without the payment to me of any royalty thereon.

I claim:

The ornamental design for a cap, substantially as shown.
